UNITED STATES PATENT OFFICE

WILLIAM L. TOLER, OF MOUNDS, ILLINOIS

DISPLAY STAND

Application filed August 15, 1928. Serial No. 299,831.

The invention relates to store furniture and more particularly to means for the display of goods, whereby to attract attention and prevent their exposure to dampness, dust and promiscuous handling.

The invention contemplates a case which is readily portable and includes ample storage space for reserve stock besides presenting a large area for the effective display of the goods to be exhibited for sale.

The invention consists essentially of a cabinet having supporting means for the merchandise to be exhibited and transparent protecting means for covering the goods to prevent miscellaneous handling thereof and exposure to dampness, dust and other deteriorating influences, while at the same time admitting of a full and unobstructed view thereof from different angles.

While the drawings illustrate a preferred embodiment of the invention, it is to be understood that in adapting the means to meet specific needs and requirements, the design may be varied and such other changes in the minor details of construction may be resorted to within the scope of the invention as claimed, without departing from the spirit thereof.

For a full understanding of the invention and the merits thereof, reference is to be had in the following description and the drawings hereto attached, in which:

Figure 1 is a perspective view of a display case embodying the invention as seen from the rear.

Figure 2 is a front perspective view of the case.

Figure 3 is a vertical, central, transverse, sectional view of the case.

Figure 4 is a horizontal, sectional view of the case taken on a line above the shelves.

Corresponding and like parts are referred to in the following description and designated in the several views of the drawings by like reference characters.

The case includes a cabinet having a glass front and top, the latter being slightly inclined and adapted to support any goods or objects placed thereon. Any suitable ma-

terial may be employed in the construction and as shown the case embodies corner posts 1, paneled ends 2, a top 3, bottom 4 and an open front and back, which includes suitable closures. The top 3 is hinged at its forward edge to the front of the cabinet and comprises a frame and plate glass, the frame being of a size to rest upon the top of the enclosing walls and admits of the use of plate glass of a maximum size so as not to obstruct any of the view when inspecting merchandise disposed adjacent the top for observation. The front of the case is closed by similar glass plates which are mounted to slide laterally and overlap at their inner ends.

A vertical partition 5 divides the case into a rear storage space and a front show space. The partition 5 is located a short distance in the rear of the front 4a and extends from the bottom 4 to within a short distance of the top 3. The show space is closed at its lower end by means of a bottom 6 which is located some distance above the bottom 4 of the storage space. A shelf 7 is located intermediate the top and bottom of the show space and extends from the partition 5 to within a short distance of the front 4a.

Goods arranged within the show space 80 may be disposed upon the bottom 6 and shelf 7 and if found advantageous may be supported upon the partition 5. The goods displayed within the show space may be readily inspected through the glass front 4a. The show space is accessible by sliding the glass plates 42 towards the right and left as will be readily appreciated.

A sub-top is disposed adjacent the top 3 and inclines forwardly and downwardly from the rear of the case and constitutes a display floor for receiving sundry merchandise to be exhibited. The sub-top 8 is spaced a short distance from the top 3 and extends over the partition 5 thereby presenting a maximum surface for the display of goods which may be readily inspected through the glass forming the major part of the top 3.

The sub-top extends over and closes the 100

upper portion of the show and storage spaces.

A horizontal partition 9 divides the storage space into upper and lower compartments, which are closed by doors 10 and 11, which are hinged at their lower edges to swing outwardly and downwardly, folding braces 12 being provided to support the doors in lowered position as indicated most clearly in Figure 1 of the drawings. The reserve stock is placed upon the partition 9 and bottom 4 and is conveniently at hand to supply the demand for any article displayed in the case, thereby facilitating and saving time in the transaction of business.

Having thus described the invention, I claim:

A display and storage case comprising a cabinet having corner posts, and walls carried by said posts, upper and lower strips carried by said posts at the front and rear of the cabinet and an intermediate strip between the rear posts, a transparent top hingedly mounted for opening and closing, a sub-top in said cabinet extending between the upper front and rear strips at a downward incline towards the front and spaced from the transparent top to form a display chamber having a forwardly sloping bottom, a vertical partition extending between said end walls in spaced relation to the front of the cabinet to divide the cabinet into a front display chamber and rear storage chamber, a bottom for the front display chamber extending forwardly from the vertical partition between the end walls and resting upon the lower front strip and projecting forwardly therefrom, transparent front panels supported by the upper front strip and bottom of the front display chamber and slideable longitudinally of the cabinet into and out of a closed position, a bottom for the storage chamber extending rearwardly from the vertical partition to the lower rear strip, a horizontal partition in the storage chamber, and doors for the storage chamber hinged to the lower and intermediate rear strips.

In testimony whereof I affix my signature.
WILLIAM L. TOLER. [L. S.]
